STRIKING CASTING

Donald S. Barrows, Rochester, N. Y., assignor
to The Symington Company, New York, N. Y.,
a corporation of Maryland

Application January 10, 1928, Serial No. 245,744

10 Claims. (Cl. 213—21)

This invention relates to combined striking castings for railway cars and more particularly to such adapted to receive replaceable wear blocks and coupler centering devices.

5 The principal object of my invention, generally considered, is to provide a combined casting formed with portions serving, respectively, as a coupler stop or striking casting and a sill tie member and provided with means for connecting said casting to the associated sills and sill cover plate of a car, a removable wear block being provided above the stem of an associated coupler and a coupler centering device provided therebeneath, whereby upon removal of said block and centering 10 device a coupler of the swivel butt type or one with a relatively large butt may be readily applied or removed.

An object of my invention is to provide a combined striking casting and coupler carrier member 20 suitable for use with a standard or full size swivel butt coupler or one having a butt considerably larger or deeper than the stem and adapted to receive a top wear block and a coupler centering and carrying device simultaneously retained by common fastenings and so formed that upon removal thereof the butt of a swivel butt coupler 25 may be readily applied or withdrawn.

Another object of my invention is to provide a combined striking casting and sill tie member 30 adapted for receiving a striking block and coupler carrying and centering block respectively disposed above and below the stem of an associated coupler, said upper block being adjustable up and down to maintain the top coupler clearance at a practical minimum.

A further object of my invention is to provide a combined striking casting for use with railway cars adapted to receive a striking wear block which is reversible and renewable upon wear or break- 40 age.

A still further object of my invention is to provide a combined casting adapted for connection with the center sills of a car and provided with a coupler supporting and centering block, and a striking portion formed with pockets adapted to receive a striking wear block, said pockets being large enough to permit vertical movement of said striking wear block, adjusting washers or liners being provided between said block and the casting 45 for positioning the same at the desired elevation, common retaining pins being also provided for holding said block and the centering device in place and cotters extending through bosses on said combined casting and above said pins for locking the same in place.

Other objects and advantages of the invention relating to the particular arrangement and construction of the various parts will become apparent as the description proceeds.

Referring to the drawings illustrating my invention, the scope whereof is defined by the appended claims.—

Figure 1 is a plan view, partly in horizontal section, illustrating an embodiment of my combined casting with an associated coupler, yoke, 10 connecting key and center sills.

Figure 2 is a side elevational view of said casting connected to the associated sills, the associated coupler, yoke and connecting key being removed.

Figure 3 is a front elevational view, partly in vertical section, of the combined casting and its parts detached from the car underframe.

Figure 4 is a longitudinal vertical sectional view of the construction illustrated in Figure 1, the 20 yoke being omitted.

Referring to the drawings in detail, like parts being designated by like reference characters, there is shown a combined casting 1, formed with a coupler striking or stop portion 2, a sill tie portion 3, and vertical side or connecting portions 4. The sill tie member 3 preferably curves downwardly between the lower ends of the side portions 4 so that its central portion is disposed lower than its end portions. The sill tie portion is disposed a sufficient distance beneath the striking portion 2 so that the swivel butt 5 of the coupler 6 may readily be inserted and withdrawn before application of the striking wear block 7 and centering block or device 8 to be described in detail 35 hereafter.

The side portions 4 of the casting are desirably formed with rearwardly extending ear or web portions 9, preferably lying on the outside of and adjacent the web portions 10 of the center or draft 40 sills 11 and connected thereto by a plurality of rivets 12. Said web portions 9 are also preferably bifurcated or formed as upper and lower sections 13 and 14, respectively, leaving notches 15 therebetween, said notches partially embracing 45 the slots 16 provided in the associated center sills 11 for the reception of the usual form of draft key 17, which serves to connect the coupler 6 with the yoke 18. For strengthening the webs of the sills around the slots 16 rearwardly of the 50 sections 13 and 14, partial cheek plates of the usual form (not shown) may be provided to supplement said sections which form, in effect, the forward portions of cheek plates.

The striking portion 2 is preferably formed 55

with a rearwardly extending web or flange 19 preferably downwardly offset with respect to the forward portion so that the top thereof lies on a level with the tops of the sills 11 and is adapted 5 for connection with the sill cover plate (not shown), said web being apertured for connecting rivets or the like, as indicated at 20. Said web or shelf portion 19 is preferably strengthened by a depending web or flange 21 and rearwardly extending tapering webs 22 which gradually decrease in depth and merge into the web 19.

The upper ends of the side portions 4 are formed with pockets 23 defined by the uppermost web of the striking casting 2, the vertical webs 24 15 of the side portions 4 which at the pockets 23 are preferably outwardly offset as illustrated, horizontal flanges, webs or walls 25 extending inwardly from and connecting the offset portions of said web 24 and the depending web or flange 20 21, previously described. Disposed in said pockets 23 is a striking wear block 7, the ends of which rest and are supported on the flanges 25 and the front web of which normally extends slightly 25 forward of the front edge of the striking portion 2, whereby upon buff the associated coupler normally engages the wear block 7 which relieves the striking portion 2 of wear. The pockets 23 are somewhat larger in vertical dimension than the wear block 7, whereby vertical adjustment of said 30 block is permitted, said adjustment being desirably effected by positioning shims or washers 26 above or below said block as desired. Said wear block 7 is desirably formed box-shaped in section or is a hollow beam substantially rectangular in cross-section, the front web 27, however, being desirably thicker than the other webs 35 on account of the increased wear thereon, it being understood, however, that this is not necessary, as the block is reversible.

40. Beneath the stem of the coupler 6 and above the sill tie portion 3, a centering block or device 8 is provided, said block preferably swinging between the front and rear walls 28 and 29 of the casting or in the hollow space provided between 45 said walls. In order to provide for sidewise movement of said block 8, the same is preferably swung on links 30 at either end thereof, said links preferably being T-shaped at their ends or provided with outstanding lugs 31, the upper of which are 50 received in and supported on bearing flanges 32 extending inwardly from the walls 28 and 29 of the casting and the lower of which support the ends of the centering block or casting 8, said ends for that purpose being bifurcated and embracing 55 the links with the bifurcated portions notched, as indicated at 33, to receive the lugs 31 on the links. Said lugs 31 are preferably tapered or decreased in size outwardly so that they tend to maintain a central position between the bearings 32, which are preferably provided with corresponding depressions or pockets 34, and the bearing portions 33 on the centering block 8.

Although said centering block may be of any desired form, in the present embodiment it is 65 shown as substantially I-shaped in section at its intermediate portions, the flanges 35 and 36 thereof being rigidified with respect to the web 37 by vertical gusset webs 38, as illustrated. Said block 70 8 is preferably deepest at its central portion, the lower flange 36 curving upwardly and outwardly toward the bearing portions 33 at the ends thereof. The upper flange 35 serves to directly support the coupler 6 and the end portions of said block are raised, as indicated at 39, for preventing sidewise slippage of the coupler with respect thereto.

The sill tie portion 3 beneath the coupler centering and carrying device 8 is preferably generally U-shaped in cross-section, the walls 28 and 29 for that purpose being connected by a web 40, said walls, however, directly beneath the centering device 8 being preferably provided with shelf or inwardly flanged portions 41 braced by gusset portions 42 for limiting downward movement of the centering device 8 with respect thereto. Said centering device is readily inserted or removed 10 sidewise between the webs 28 and 29 of the casting above the flanges 41 and web 40 and beneath the supporting portions 32.

The striking block 7 and coupler carrier and centering device 8 are preferably retained in position by common fastening or connecting means which preferably take the form of vertical pins or rods 43, received in apertures 44 in the webs or flanges 25 connecting the offset portions of the webs 24, apertures 45 in the ends of striking wear 20 block 7, apertures 46 in the washers 26, and apertures 47 in the top of the combined casting or striking portion 2 thereof. For securely locking the rods or pins 43 in place, the striking portion 2 of the casting is preferably formed with up-standing collars or bosses 48 around the apertures 37, which collars are provided with horizontal apertures 49 therethrough for receiving cotter pins or other retaining devices 50, whereby undesired removal or loss of the pins 43 is prevented.

Inasmuch as the lower ends of said pins 43 engage the tops of the supporting links 30 for the centering device 8, said links are retained in position and prevented from loss or undesired removal by the same fastening means as hold 35 the striking block 7 in place. Although these pins prevent unseating of the links from their bearings 34, they of course do not prevent removal of the centering device or block 8 from the lower ends of the links. This is, however, 40 prevented when the coupler is in place, by the limited clearance between said centering device and coupler, whereby it is impossible to remove either the centering device or the striking block 45 while the pins 43 are in position.

From the foregoing description, taken in connection with the accompanying drawings, it will be seen that I have devised a combined striking casting and sill tie member which is formed with pockets in the upper portions thereof to receive a top or striking wear block and the lower portion thereof is formed to receive a coupler supporting and centering device or block, both of said blocks being simultaneously retained by the same or common fastenings. Any large 55 amount of shear on the fastenings 43 is avoided by having the wear block 7 normally abut the flange 21. The upper wear block is formed adjustable up and down for keeping the top clearance at a practical minimum. Said adjusting 60 means preferably takes the form of washers which are held in place by the pins which retain the locking and centering device in position. The striking casting is so formed that upon removal of the block and centering device, an aperture of ample size is provided for the insertion or withdrawal of the coupler 6 and particularly the swivel butt portion 5 thereof which, as will be understood, is of greater size than the butt of a rigid stem coupler. By providing a removable 70 block above the stem in combination with the centering device, not only is it possible to insert and remove the butt of the coupler while assembled, especially as the flange or web 21 is decreased in depth above said coupler and the sill 75

tie portion downwardly curved directly beneath the coupler, but the clearance above said coupler may be maintained by adjusting the position of the upper block 7 by changing the washers 46.

On account of providing a removable block 7 above the stem of the associated coupler 6 rather than having the striking portion formed integrally with the casting, I am enabled to decrease the overall height of the combined casting, as will be understood, and at the same time provide a casting which is more desirable in other respects in that the upper wearing portions thereof are renewable.

Having now described my invention, I claim:

1. A combined casting comprising portions serving, respectively, as a striking casting and sill tie member, said casting being formed with pockets adjacent the upper portion thereof and an upper wear block received in said pockets, the lower portion of said casting being formed hollow for receiving a centering device and provided with bearing portions for swingably supporting said device, a centering device supported on said bearings and received in said hollow portion, and common fastenings simultaneously retaining said upper block and centering device in place, said block and centering device being spaced to receive the stem of an associated coupler therebetween.

2. A combined casting comprising portions serving, respectively, as a striking casting and sill tie member spaced to leave a coupler stem opening, said portions being connected by sides formed with rearward continuations adapted for connection with associated sills, said sides being formed with pockets disposed adjacent the upper ends thereof, a reversible striking wear block received in said pockets and adapted to restrict the opening for limiting movement of the coupler, and a coupler centering device swingably mounted between portions of the sides of the casting beneath said block, said block and centering device being held in place by common retainers and spaced for holding the stem of an associated coupler therebetween, and when removed leaving the coupler stem opening large enough to provide for receiving or withdrawing an enlarged butt portion thereon.

3. A combined casting comprising portions serving, respectively, as a striking casting and sill tie member, a wear block held in place adjacent the striking portion and a centering device movably mounted above the sill tie portion and spaced from the wear block to receive the stem of an associated coupler therebetween, the ends of said block and the adjacent portions of the casting being formed with registering apertures, retaining pins insertable through said apertures for simultaneously locking said block and centering device in place, and locking means disposed above said pins for preventing undesired removal thereof.

4. A combined casting comprising portions serving respectively as a striking casting and sill tie member, a wear block received in said casting, a centering device disposed beneath said wear block, and common fastenings simultaneously retaining said block and centering device in place.

5. A combined casting comprising portions serving respectively as a striking casting and sill tie member, a wear block disposed adjacent the striking portion and a centering device mounted above the sill tie portion and spaced from said block to receive the stem of an associated coupler

therebetween, and retaining pins adapted to pass through the ends of said block for simultaneously locking it and the centering device in place.

6. A combined casting provided with a coupler stem receiving opening, pockets in its upper part, and comprising portions serving, respectively, as a striking casting and sill tie member, a wear block with its ends seated in said pockets, its intermediate portion restricting said opening, serving to protect the casting from wear and held in place adjacent the striking portion, a centering device supported adjacent the sill tie portion from positions directly beneath the pockets receiving the ends of the wear block, and common fastenings for said block and centering device, said block and centering device being spaced to receive the stem of an associated coupler therebetween.

7. A combined casting comprising portions serving respectively as a striking casting and sill tie member connected by side portions and defining a coupler stem receiving aperture, a centering device, comprising a coupler supporting block and a swing link at each end, movably mounted above the sill tie portion and spaced from the striking portion of the casting to receive the stem of an associated coupler therebetween, upright retaining pins inserted through apertures in said casting and with their lower ends engaging the tops for holding of said links said centering device in place, and locking means disposed above said pins for preventing undesired removal thereof.

8. A combined casting comprising portions serving, respectively, as a striking casting and sill tie member, said portions being spaced to permit the insertion of the butt of a swivel butt coupler therebetween, those portions of the casting connecting the striking and sill tie portions being pocketed, and a wear block received in said pocketed portions adjacent the upper part of said casting, said block being vertically adjustable to keep the top clearance above the stem of an associated coupler at a practical minimum and serving to limit upward movement of said coupler, the lower portion of said casting being formed with spaced walls and provided with bearings, links mounted in said bearings, a common fastener for each end of said block and the link therebeneath, and a centering device, serving to support and limit downward movement of said coupler, supported by said links, said centering device and wear block being spaced for receiving the stem of a coupler therebetween, and when removed both contributing to the enlargement of the coupler stem opening so that a stem with an enlarged butt portion may be inserted or withdrawn.

9. A combined casting with a coupler stem opening and comprising portions serving, respectively, as a striking casting and sill tie member, a wear block receivable in pockets adjacent the top of said casting, said block serving as a coupler stop member or striking wear block, and a swinging centering device mounted therebeneath, said block and centering device being simultaneously secured by the same retainers, and cooperating to restrict the coupler stem opening for guiding the stem of an associated coupler and when removed enlarging the opening through the casting sufficiently for receiving the stem of a coupler with an enlarged butt.

10. A combined casting, with an opening for receiving a coupler stem, comprising portions serving, respectively, as a striking casting and

sill tie member, a renewable wear block supported and locked in place adjacent the striking portion and serving to restrict the size of the coupler opening, a coupler centering device mounted beneath said block a sufficient distance for receiving the stem of an associated coupler between it and the block while contributing to the

restriction of the opening, and common means for securing said block and centering device, said casting being formed with an aperture therethrough sufficient for receiving the enlarged butt of a coupler upon removal of the centering device and wear block. 5

DONALD S. BARROWS.
